UNITED STATES PATENT OFFICE.

JAMES R. WOODROUGH, OF CINCINNATI, OHIO, ASSIGNOR TO WOODROUGH
& McPARLIN, OF SAME PLACE.

DESIGN FOR SAW-HANDLES.

SPECIFICATION forming part of Design No. 11,603, dated January 13, 1880.

Application filed October 22, 1879. Term of patent 7 years.

To all whom it may concern:

Be it known that I, JAMES R. WOODROUGH, of Cincinnati, Hamilton county, Ohio, have originated and designed a new Pattern for 5 Handsaw-Handles, of which the following is a full, clear, and exact description, reference being had to the accompanying drawing, making a part of this specification.

My design consists in the application of an 10 ornamental head to the front end of a saw-handle, &c.

I prefer to carve the head from the same piece of which the handle is constructed; but it may be made of a separate piece of wood

or metal and attached to the handle, should 15 the manufacturer so desire, and still fall within the scope of my design.

What I claim as my invention, and desire to secure by Letters Patent, is—

A design for handsaw-handles, consisting 20 of the ordinary form of handle, its front end being provided with an ornamental head projecting from said front end over the blade of the saw, substantially as shown.

JAS. R. WOODROUGH.
